UNITED STATES PATENT OFFICE.

MATTHEW KLEIN, OF BILLINGS, MONTANA, ASSIGNOR OF ONE-HALF TO HART-ALBIN CO., OF BILLINGS, MONTANA.

MERCHANDISE-TICKET-AUDITING DEVICE.

Application filed August 30, 1927. Serial No. 216,428.

- This invention is an improvement upon and development of the device disclosed in my prior copending application Serial No. 650, filed January 5, 1925.
- 5 The invention includes a mechanism whereby the obtaining of an accurate sales record is facilitated; and especially by operating directly on price tickets for the merchandise while this ticket is attached thereto. Thus 10 according to one form of my invention a part of the ticket can be severed, leaving the other part of the ticket on the goods, and the severed portion is then used as an original record of the sales transaction.
- 15 The present invention provides an improvement over my system disclosed in my above identified application. In the auditing departments of large stores trouble has been experienced in the past due to the difficulty of 20 guaranteeing the correctness of the original entry of a sales transaction. Ordinarily in the past sales were first entered upon slips of paper, the data being taken by the clerk from the price tickets. This transference of 25 data, depending as it does upon the carefulness of the person making the sales, may easily result in error.
- It is thus a main object of my present invention to reduce the likelihood of errors to a 30 minimum; and especially by utilizing at least a portion of the price ticket on the merchandise being sold as the original entry; thus evading the necessity of transferring the record from the ticket.
- 35 The apparatus thus incorporates from the price ticket, data that is premade, as well as authorized. These data, since they appear on a price ticket, are displayed with the merchandise. The data are furthermore incorporated on a recipient, such as a card or tape.
- 40 It is another object of my invention to provide a check on the cash drawers; especially by having these cash drawers interlocked with the compartment in which the completed 45 records are deposited; and in this way to keep an accurate record of the sales made by each clerk and to facilitate classification of the records, and of checking up of these records with the money taken in during any definite 50 period.
- It is still another object of my invention to make it necessary for the operator who makes the sales to provide a visual as well as an audi- ble indication whenever the operator is setting the recording mechanism to the desired 55 operation. This provides a check on sales, since any irregularity in the operation of the mechanism is quite likely to be detected by store inspectors or store shoppers.
- It is still another object of my invention to 60 make it possible to detect false or unauthorized operation of the mechanism, such as may be surreptitiously attempted by the clerk in order to unlock the cash drawer. This is accomplished by insuring that a record is made 65 and deposited in a space unavailable to the operator, for each unlocking operation of the mechanism.
- It is still another object of my invention to 70 make it possible to add to the record obtained by the aid of my mechanism, data identifying the customer and his charge limit in the store. This object is accomplished by the insertion at will of plates serving to imprint upon the record this supplementary data. It 75 is the intention that such plates be carried by each customer, or that such plates be kept for the customer either at a central location in the store or in each of the departments. Each of the plates carries a facsimile of the customer's 80 or credit manager's signatures, or both, whereby proper check can be kept against unauthorized use of the plates. The use of these plates facilitates the authorization of credit, or charge, transactions. Thus when 85 a customer desires to utilize his plate to make a credit purchase the clerk who is to make the sale will inspect this plate, which carries an identifying number, and will compare it with a list furnished to her periodically, such as 90 each day, and containing those numbers of identifying plates that are not to be honored by her without authorization from a higher authority. If the number of the customer's plate is absent from the list, the customer's 95 signature or the credit manager's signature gives the clerk the authority to make the sale within the limit clearly marked on the plate. This method of authorization materially shortens the credit transaction, including the 100 record of the customer's name, amount of the purchase, date, or any other data that may be desirable. The obtaining of all this essential information in printing insures clarity of the record and obviates the possibility of securing poorly written or illegible records

such as may be obtained when these records are written by hand. The complete printed record, including the record taken from the price ticket and that taken from the customer's identifying plate, is now present as a unit printed record, which can be used by the auditing department as a charge ticket against the customer's account.

Viewing the invention from yet another standpoint, it may be stated to lie in the use of a price tag or ticket to control the record of the amount of the sale, a part of the ticket at least acting as an original record. The operation of acting upon the price tag for obtaining the record therefrom serves to control the opening of the cash and supply drawers, and furnishes a clear proof of the selling price of each article operated upon. The supplemental record can be used to identify the operator, the character of the sale, the date of the sale and the serial number of the transaction, as well as any other desired data. The tape which is used in the present instance as a backing for the price tag makes the record readily usable and facilitates mechanical classification. The visible indication publicly displays for inspection the details of the record that the machine is making or about to make. The interlocking control of the supply and cash drawers ensures that a registration be made by the operator before that operator gains access to the cash drawer for making change or for depositing money, or for obtaining material for wrapping.

Since the mechanism is operated by a source of power such as a motor or a heavy spring, the operation of recording can be quickly accomplished and there is, accordingly, a considerable saving in time, which becomes important during those periods when customers are waiting to be served.

The mechanical classification provided by my mechanism secures a check against which the cash receipt of each operation must balance. This classification also eliminates the manual labor usually required to separate the sale slips in clerk order or by number.

The necessity of utilizing the price tag in connection with the machine for registering ensures that the clerk will be forced to operate that machine when making a sale before delivery of the goods to the customer. If she fails to utilize the price tag in connection with the recording mechanism she lays herself open to detection or suspicion.

The audible signals provided are obtained by the aid of gongs or bells operated in response to the opening of the drawers. Each gong or bell can have a distinctive sound showing which drawer is opened and also attracts the attention of a store inspector or store shopper to the transaction for ready check upon the sales force.

I also provide an indicator showing the number of articles sold in any particular

transaction. This provides a public inspection of the number of price tag records made during that transaction, and thus provides an additional check upon the sales force.

It is still another object of my invention to cut off the price tag by the aid of a peculiar punch, the form of which may be varied as required. In this way the machine, or the store, or the date, or other desired identification of the sales is obtained. It furnishes evidence of the operation of the machine, and in its absence indicates that the price tag was improperly tampered with.

The mechanism may take any of a number of forms; in the present instance I utilize a device whereby certain data are printed on the tape or paper strip to which the price ticket is attached. These data may be varied as desired, and may indicate whether the sale is a cash or a charge sale, that is, the commercial character of the transaction; and may carry the identifying number of the clerk, or both. A compartment is provided for each clerk, into which the sales checks are automatically distributed, so that, at the close of any predetermined interval, the tickets of each compartment will show the sales made by that particular clerk. A plurality of cash drawers is also provided, and the proper cash drawer is selected and automatically opened simultaneously with the selection of the compartment for receiving the ticket.

Other objects of the invention will be apparent from the following detailed description, and will be set forth in the appended claims.

In the drawings:

Figure 26 is a side elevation of the same.

Figure 27 is a horizontal section on the line 27-27 of Figure 26.

30 Figure 28 is a rear elevation of the lower part of Figure 26.

Figure 29 is a plan view of one side of the identification print.

Figure 30 is a plan view of the opposite side thereof.

35 Figure 31 is a detail sectional view, taken along plane 31-31 of Fig. 5.

The main portion of the mechanism is carried by a base member 1 extending upwardly from which, near the center portion thereof, 40 is a body or frame member 2. Suitable brackets are also provided wherever necessary, attached either to the frame member or to the base, for supporting the various parts of the mechanism. A power source for the

45 operation may be provided, for example, an electric motor 3 is mounted on the base member, and is connected to a driving shaft 4. This shaft 4 at its opposite end carries a worm

50 which meshes with a worm gear shown in dotted lines in Figure 8. This worm gear is carried by a short sleeve 6' mounted to rotate on the shaft 6. This shaft 6 is arranged, when the motor is actuated, to be rotated through a definite cycle, such as one revolution,

55 whereby the record obtaining mechanism is once actuated, and then the motor 3 is caused to come to rest automatically, and until such time as further action is desired. For connection and disconnection preferably

60 a clutch mechanism is provided for connecting the sleeve 6' to the shaft 6 when it is desired to rotate the latter. This clutch mechanism consists of a disc 7 (Figs. 8 and 14) which is fast on the shaft 6 and carries a

65 spring actuated pawl 8 adapted to engage

with a ratchet wheel 9 carried by the sleeve 6'. An arm 10 which is pivotally supported by the base extends upwardly into the path of a pin 11 carried by the pawl 8 so that, when the pin comes in contact with the arm 10, the pawl will be lifted out of engagement with the ratchet wheel 9, and the sleeve 6' may rotate without transmitting a movement of rotation to the shaft 6. When it is desired to set the shaft 6 into movement, a ratchet wheel 12, against which the arm 10 is drawn by means of a spring 13, is actuated through mechanism hereinafter described to move the arm 10 out of the path of the pin 11 and allow the pawl 8 to drop into engagement with the ratchet wheel 9, whereupon the motion of the sleeve 6' will be transmitted to the shaft 6.

Near its other end the shaft 6 carries a gear 14 which meshes with an idler gear 15, which in turn meshes with a gear 16. The gear 16 is enmeshed with both gears 17 and 18, while the gear 18 is enmeshed with the gear 19. The gear 16 is mounted on a shaft 20, the gear 17 on a shaft 21, and the gear 18 on a shaft 22.

Practically all of the operations of the machine are brought about by the rotation of this train of gearing, and various features will be described separately. I shall first describe the mechanism for cutting off a part of a long tape to which the price ticket is attached. The gear 16 has a cam 23 fixed to its shaft 20, which is in contact with a pin 24 pivoted to a pivoted arm 25, which is connected to operate a cutting blade 26 (Fig. 3) which coacts with a companion blade 27 fixed to the frame 2 (Figs. 2, 3, 5 and 6).

It will be evident from Figure 6 that the arm 25 is operatively connected to the slide 27', which is normally drawn in one direction by a spring 27''. It is obvious that for one rotation of the gear 16 and cam 23 the movable knife 26 will be given one complete movement to and from its normal position. This knife acts to sever the paper strip and pin ticket affixed thereto, as will be herein-after set forth.

The opposite end of the shaft 20 carries a cam 28 having a cut away portion 29 (see Figs. 5 and 31). The function of this cam is to operate a platen 30 for the printing mechanism. This platen is pivoted at 31 on suitable arms 32, and the platen pads proper are indicated at 33. A compression spring 34 presses upwardly against the bottom side of the platen, and keeps an upwardly projecting lug 35 in constant contact with the periphery of the cam 28. It is obvious that, as the cam is rotated, the platen will be lowered from or raised against the printing wheels and the tape, which lies between the wheels and the platen.

The printing mechanism for adding to the record the number of the total operations of the machine is indicated generally at 36

(Fig. 5). It is advanced step by step through the usual driving means 37, which is operated by a link 38 connected to one end of a lever 39 pivoted to a bracket 40 to turn about a shaft 41, and having an arm 42 which is in constant engagement with a cam 43 carried by the shaft 21 of the gear wheel 17 (see Figures 3 and 6). Each complete operation of the machine which rotates the gear wheel 17 once will obviously advance the numbering wheel one unit, and the number on the backing which supports the severed portion will show how often the machine has been operated.

15 The shaft 21 extends through the frame 2 and at its opposite end is connected to a part of the stitching mechanism; particularly to feed stapling or stitching wire to the stitching mechanism. As shown in Figures 1, 2 and 20, the shaft 21 carries a gear 44 which drives a companion gear 45. The shaft extends beyond the gear wheel 44 and carries a wire engaging friction roller 46 having a cam portion 47 on its periphery. This friction roller cooperates with a companion friction wheel 48 and operates to feed wire 49 from a reel 50 into the stitcher head. As shown in Figures 2 and 20, the staple forming wire 49 passes in engagement with a series 30 of projecting pins or lugs 51, at least some of which are mounted under tension of a spring 52. These lugs tend to straighten the wire as it is fed forward, and to prevent any back lash thereof after the gripping rollers 46 and 48 are released. The cam portion 47 on the friction wheel 44 is so arranged that the two friction wheels are allowed to grip and advance the wire for a predetermined distance, corresponding to the length of the low portion 40 of the cam. Then, as the cam portion 47 engages with the lower friction roller 48, the two rollers are slightly separated to prevent any further gripping and advancing of the staple wire. The lower friction roller is 45 under spring tension, being carried by an arm 53 which is normally urged in one direction by a spring 54. This prevents the two gears from becoming entirely disengaged.

50 The staple forming and affixing mechanism is best illustrated in Figures 20 to 24. The wire 49 is advanced into the stitcher head, into the path of movement of a cutting and forming tool 55, a forming block or anvil 56, and a driving tool 57. The tools 55 and 57 are slidably mounted in raceways within the stitcher body. These are normally spring pressed upward, so that their upper ends are in wiping contact with cams 58 and 59 mounted on a shaft 62 driven by the gear wheel 19, which 55 imparts one complete revolution to these cams for one actuation of the mechanism. This shaft also carries a cam 60 which operates a ticket cutting blade 61. The forming block or anvil 56 is formed with an upwardly extending hook member 63 which engages the

cutaway portion 64 with the stitcher head. This block is kept in the position shown in Figure 23 by a spring 65. The inner wall of the forming block 56 is shaped slanting to correspond with the lower edge of the driving tool 57, so that upon a downward thrust of this driving tool the forming block will be moved rearwardly to permit the driving tool to force the staple downwardly through the paper and to be crushed in the forming groove 66. Before the staple is thus urged downwardly carrying the formed staple with it, which is slidably embraced within the grooves 75 of the cutting and forming tool 55. These grooves extend to the bottom of the tool, thus insuring the positive delivery of the staple for insertion through the paper in an upright position. It will be noted that the cutting 80 knife 61 is moved downward and received by a female die portion 67 formed beneath the stitcher head. This insures a clean cut of the ticket and prevents too much drag on the knife in its forward travel. A ticket guide 68 shown in Figure 2 is provided so that the operator can readily position the ticket and insert it in the proper position to be operated upon by the stitching mechanism and associated parts. It is necessary for the operator only to press the ticket downward to the bottom of the guide and then move it inwardly the desired distance.

There is also provided the ticket advancing means for engaging and feeding the paper carried by a roll 69. This is best shown in Fig. 2. The paper, as it comes from the roll 69, is drawn over a yielding bail member 70, under a friction arm 71, and thence into the stitching head. For the purpose of feeding the paper sheet, there is provided a friction roll 71^a which engages the paper strip, and this roll is carried by an arm 72 normally forced upward by a spring 73. This roll presses the paper against the periphery of the segment 26' (Fig. 5), which, as above described, is driven from the shaft 21. This complete operation of the machine will, therefore, result in feeding forward the paper a predetermined distance.

105 After the paper tape has received the pin ticket and has been severed by the knives 26 and 27, it is pushed outwardly by the next advancing movement of the paper into position to be engaged by a discharging mechanism. 110 This discharging mechanism will discharge the uniform tickets into a receptacle which need not be attached to the machine, nor does it need to be in the form illustrated. As 115 illustrated and described, however, this ticket 120

receptacle comprises a plurality of compartments for a purpose hereinafter set forth, and the discharge mechanism operates to throw said tickets into said receptacle. This discharge mechanism comprises an arcuate member 74 that is arranged to rotate so as to grip the completed record between it and a friction roller 82. For this purpose it is mounted to rotate about an axis 75, and is urged to discharge position by a spring. The drawings show gripper 74 after the discharging function is completed. However it is latched against movement by the downward movement of blade 26 prior to its cutting operation. This latching is accomplished by an arm 76 associated with the cutting blade 26 as by being carried by the slide member 27' above described (see Figure 6). The upper end of the arm 76 is provided with an elongated slot 77 embracing a pin 78. As the cutting blade 26 is moved downwardly, the arm 76 is moved downwardly with it and permits a pawl or detent 79 to hold the wheel 81 against return movement, said wheel being connected to the shaft 75 that carries the discharging member 74 and rotated to latched position by engagement of its pin 78 by member 76. Upon upward cutting movement of blade 26 the member 76 is moved upwardly and after the cutting is accomplished, the top of member 76 disengages the same from a cut away portion 80 on disc 81. The pawl 79 engages with the notch 80 long enough to permit the advancing paper to be first cut and brought to rest between the paper discharging arm 74 and the contact roller 82 beneath the same. Whenever the arm 76 moves upwardly and disengages the pawl, the arm 74 is allowed to function and moves the ticket which is gripped by the wheel 82, (Fig. 5), into the desired compartment, which has been brought into alignment with a shelf portion 83 embracing the friction wheel 82. The construction of the ticket receptacle will be hereinafter described.

A ribbon is provided for cooperation with the printing wheels, and for the purpose of feeding this ribbon the following mechanism is employed, which will be understood by reference to Figures 1, 3, 5, 6, and 7.

A pair of ribbon spools 84 and 85 have shafts 86 and 87 respectively which carry ratchet wheels 88 and 89. The ribbon 90 passes from the spool 84 downwardly thru a guide 92 (Fig. 5), over the top of the platen 33, and beneath the printing wheels, and thence upwardly through a guide 91, where it is wound back on the spool 85. The spools are driven automatically by the following mechanism, shown in detail in Figure 7. An arm 93 is pivotally mounted on a shaft 22 of the gear wheel 18. This arm 93 extends upwardly and carries a yoke 95 adapted to embrace a cam member 96, which is secured to the shaft 62 of the gear wheel 19. When ever the gear 19 and this cam are rotated, it is obvious that the yoke will be given a to and fro movement which will also be transmitted to the arm 93. This arm pivotally carries a transverse rocking lever or link 99, which serves as a guide for a longitudinally adjustable pawl bar 97, carrying a pawl 98 at each end thereof for operation of the ribbon feed. This bar 97 is shown in Fig. 7 as shifted as far toward the left as possible, to make the left hand pawl 98 active. The guide for the bar can be in the form of a pin 97' carried by bar 97, engaging in a slot 99' in lever 99. At the other side of the pivot for lever 99, this lever carries a pin 102 engageable in either of two depressions 102' in the lower edge of pawl bar 97. Springs 100, 101, serve to maintain the assembly yieldingly in the position of Fig. 7. The pin 102 is urged into a holding depression 102' by the spring 85 force.

When the ribbon ratchet wheel 88 (Fig. 6) is stopped because of its being fully wound, it acts as a stop for movement of bar 97 to the left, even while lever 99 is moved by arm 93. This results in a shifting of bar 97 with respect to lever 99, so that pin 97' will be at the right-hand end of slot 99', and pin 102 will be snapped into the left-hand depression 102'. Thus, so far as operative positions are concerned, the left-hand pawl 98 is retracted, and the right-hand pawl 98 is extended, making the latter pawl alone operative to operate wheel 89 (Fig. 3). When this latter wheel is stopped, the bar 97 is again automatically shifted to the position shown in Fig. 7.

I shall now describe the means for selecting the compartment into which the completed record is inserted. Extending longitudinally of the machine and rotatably mounted on bearings mounted on the frame 2, (Figs. 3 and 6) is a shaft 103, the inner edge of which is provided with a sprocket wheel 104 and a gear wheel 105. The other end of the shaft 103 rotatably supports the ticket receptacle 106, which has a rear wall 107 and a cover plate 108. Between the rear wall and the cover plate is a plurality of radially extending partition walls 109 forming compartments for the tickets 110, which are shown in position in Figure 17. Each compartment is provided with an opening 111 (Fig. 17) for the admission of tickets. The tickets are held in place by spring actuated clamping fingers 112 which are pivotally carried by the partition walls at 113 and actuated by springs 114. One end of each of these clamping fingers extends through the wheel of the receptacle and is provided with a lug 115, as shown in Figures 18 and 19. These lugs have a dual function. They have first a positioning engagement with a roller 119 carried by an arm 120, see Figure 6. This arm 120 is mounted on a rotatable shaft that 130

is oscillated when carriage 27' is moved downwardly for lowering the blade 26. Thus it is moved into and out of engagement with the lugs by the upward or downward movement 5 of the cutting blade 26. The oscillation of arm 120 (Fig. 6) is secured by mounting it on a rotatable shaft 120', carrying arm 120" that is actuated by the downward movement of slide 27'. This insures the positioning of 10 the receptacle in its proper adjusting position, after which a further rotational movement of the arm 120 and roller 119 moves the lug 115 about its axis and lifts the associated clamping finger 112 to permit admission of 15 the ticket. The finger 120, once it moves to opening position, is held in the opening position until after the discharger 74 has operated. Thus a projection 240 on arm 120 is stopped by a horizontal arm of lever 239, 20 back of which the projection 240 snaps as arm 120 moves to open position. However, when discharger 74 operates, the lever 239 is rocked by pin 241 on disc 81 so as to free finger 120, and it returns by spring pressure 25 to the closing position. On the return movement of the cutting knife, the clamping finger is released and holds the ticket firmly in its respective compartment. The periphery of the receptacle is provided with suitable 30 doors 116 hinged at 117, and provided with inspection openings 118. At the opposite side of the machine, see Figures 3 and 4, is rigidly mounted a quadrant 121 provided with a plurality of notches 122. Pivottally 35 mounted at the center of this quadrant is an arm 123. The lower portion of this arm carries a motor switch 124 which consists of two parts 125 and 126, movable with respect to each other and each carrying a contact 40 point. Another arm 127 is slidably mounted within the arm 123 and carries a pair of pins 128, one of which is adapted to engage any selected notch 122, while the other engages an extension 129 on the upper portion 45 of the motor switch, so that downward pressure on the knob of the arm 130 will close the motor switch and put the motor in operation. A shaft 131 is supported by suitable brackets parallel to the frame 132, and 50 the outer end of this shaft carries the vertical arm 123 so that a movement of the arm 123 will rotate the shaft 131 and cause a gear wheel 133 on its inner end to rotate also. This gear wheel 133 is in engagement with 55 the gear 105 on the shaft 103, which carries the ticket receiving receptacle. The notches 122 on the quadrant 121 correspond to given compartments in the receptacle. In order to 60 select any desired compartment, it is therefore necessary merely to press downwardly on the knob 130 and move the arm 123 until the desired notch is reached, and pin 128 enters the selected notch.

The selection of a desired compartment 65 also sets a printer device to mark upon the

completed record, the clerk identifying character or the character of the sale, whether charge or cash, or both. Thus gear 133 (Fig. 5) also engages the gear wheel 134 mounted on the shaft 135, the opposite end of 70 which is provided with a gear 136 engaging the gear 137, which rotates a printing wheel 188 carrying certain data such as the designating character of the account and the clerk's number. It is therefore obvious that 75 whenever the arm 123 is moved to select a particular compartment of the ticket receptacle the printing wheel will also be automatically positioned to correspond with said selection. 80

I also provide means for holding the ticket receptacle 106 in proper locked position until after the mechanism has completed the cycle. Thus on the outer face of the inner wall of the ticket receptacle is mounted a plurality of bifurcated members 139. When a compartment is properly aligned, one of these members 139 is at its lowest position in place to receive the end of an arm 140 (see Figures 3 and 10), which is pressed downwardly 90 against a spring 141 by a cam member 143 carried by the shaft 6 of the gear wheel 14. Cam 143 also serves to actuate the cash drawer unlocking means, the unlocked drawer corresponding to the selected compartment in 95 receptacle 106. Thus the arm 140 is pivoted at 142, and the opposite end thereof is provided with a downwardly extending link 144 secured to a bracket 145, which is suitably apertured to receive a plurality of rods 146. 100 These rods correspond respectively to a plurality of cash drawers 147, which are slidably mounted within a cabinet 148. It is to be understood that the base plate 1 is mounted on top of this cabinet. Each of the rods 146 is held in contact with an apertured drum 149 mounted on top of the cabinet, so that, when one of the apertures of the drum comes into registry with the uppermost end of one of the rods, this rod is permitted to be lifted 105 upwardly by its spring 150 so that the drum is locked against further movement, and the particular drawer corresponding to the rod may be opened, due to the release of its rod 146. A vertical shaft 151 is provided which 110 has a coil spring 152 attached to the bottom thereof. This rod carries a plurality of arms 153, each of which bears against the projection 154 on the associated drawer, while the other end thereof bears against a 115 coil spring 155, which, at its opposite end, bears against the back wall of the cabinet. Raising of any one of rods 146 permits a corresponding spring 155 to act on lever 153 to urge the drawers to open position. The details for this will be hereinafter described. The upper end of the shaft 151 carries a cam member 156 (see Figure 8) adapted to contact with a roller 157 on the lower end of a pawl member 158. This pawl is released, 120

130

when the cash drawer that is opened is pushed to closing position, from a wheel 161 connected to drum 165. This drum indicates the number of articles registered in one transaction, corresponding to the number of such articles sold to each customer. An advancing pawl 159 for wheel 161 is pivotally carried by the base member or top of the cabinet, and is adapted for engagement with a cam 160 of the driving shaft 6, so that each cycle of operation of the machine will cause the pawl 159 to engage the ratchet wheel 161 and rotate the same. A sprocket wheel 162 on the shaft of this ratchet wheel is connected by a sprocket chain 163 with a sprocket 164 on the shaft of an article indicating drum 165. The periphery of this indicator is provided with suitable numerals which indicate the number of purchases in the transaction. The machine is operated for each single purchase, and the article indicator will show how many purchases have been made and registered. A coil spring 166 has one end secured to the article indicator 165, and the other end to a bracket 167 which is carried by the frame 2, so that when a lever 153 acts to release the holding pawl when the opened drawer is closed, the indicator returns to zero position. This indicator is visible at a distance and shows instantly whether any drawer is open; and thus constitutes a check on the clerk.

I shall now describe how the drawer is unlocked. A hook member 168 (Fig. 8) is pivotally carried by a bracket 169 attached to a partition 170 within the cabinet, and each of the rods 146 carries a pin 171 adapted to engage the hook 168 on its upward travel, and disengage this hook from an opening in a bracket 172, thus releasing the drawer for opening and its corresponding lever 153 can move to urge the drawer to open position.

As each drawer is opened, an alarm is given by mechanism shown in detail in Figure 11. This comprises a hook 173 pivotally carried by the back of the drawer and held in one position by spring tension. As the drawer moves outwardly, the hook carries with it a bell clapper 174 until the hook is freed from the clapper, when the latter, under the influence of a spring 175, strikes the bell 176. It is to be noted that the spring 175 is of sufficient compression strength to permit the clapper to strike the bell once and then normally hold it out of contact therewith. If desired each bell 176 associated with its drawer can give a definite tone or sound to indicate which clerk is making the sale.

There is illustrated in Figures 15 and 16 the mechanism for automatically breaking the circuit and stopping the motor. When all of the transactions have been completed by the machine the drawer is closed and the indicator drum returned to its normal position. This is brought about by means 177 carried by the upper end of the rod 151. This arm is

connected by a link 178 to another pivoted arm 179 carrying a spring pressed pawl 180 in engagement with a ratchet wheel 181. It is therefore obvious that, if the rod 151 is turned in either direction, it will impart a corresponding movement to the connections described and rotate the ratchet wheel step by step. A vertical arm 182 pivotally carried by the base 1 is held in wiping contact with the ratchet wheel 181, so that, as the wheel is turned, this arm is moved inwardly and outwardly, and its motion will be transmitted through a link 183 to a lever 184 pivotally carried by a bracket 185. The upper end of the lever is provided with a yoke 186 which is adapted to engage a spring hook on the lower end of the movable part of the motor switch 126 and release the contacts, breaking the circuit thereof. Thus as the lever 153 is moved by the closing of a drawer the switch 126 is operated.

There is shown in Figures 12 and 13 a compartment for wrapping paper and the like which will be positioned, if used, in the lower part of the cabinet 148. This compartment is held closed so as to prevent use of the wrapping paper until a sale is registered, whereupon it may be opened. The paper roll 187 is rotatably carried by a bracket 188 supported from a floor member 189. A shaft 190 mounted in the bracket 188 carries a plurality of arms 191 which support a guard plate 192. Another arm 193 extends outwardly from the guard plate assembly, and is connected to a link 194, the other end of which is connected to a bell crank lever 195 pivotally mounted on a shaft 196. An extension 197 of this bell crank provides an attachment for one end of a spring 198, the other end of which is secured to the floor 189. A controlling handle 199 is slidably mounted between two rollers 200, and the inner end thereof is provided with a roller 201 adapted to engage the other arm of the bell crank lever 195. The other end of the handle 199 is provided with a finger engaging portion 202. This handle 199 has a notch 203 which engages a bifurcated bracket 204 when the handle has been moved inwardly to close the paper guard. It is obvious that after the handle is lifted to disengage the notch with bracket the spring 198, acting through the bell crank lever 195, will throw the paper guard 192 downwardly away from the paper. The usual cutting knife 205 is provided, which is held in constant engagement with the paper by any suitable spring. An arm 206 extends upwardly from the shaft 196 and lies in the path of movement of a rod 207 slidably mounted in a bracket 208. The opposite end of this rod contacts with a lug 209 on the vertical shaft 151. A block 210 is pivoted at one end in a cut out in the bottom of the lowermost drawer, which is a supply drawer for envelopes, small pieces of wrapping paper, and the like, and in the path of

125
130

the vertical arm 206. When this drawer is closed, the block 210 will fall by gravity into position shown against the vertical arm 206, which is rigidly carried by the shaft 196, so that this shaft cannot move to permit the above described movement of the paper guard. It is therefore impossible to obtain access to the wrapping paper unless an article has been sold and suitable operation of the machine has resulted in the release of one of the cash drawers, and consequent release of the other described mechanism.

The arms 153 shown in Figure 10 each has an enlarged portion 211 where they are carried by the vertical shaft 151, and this is cut away at 212 for one-fourth of its diameter. A pin 213 extends outwardly from the shaft 151 and is adapted to ride in this cut-out portion. Normally, the spring 152 influences shaft 150 in such direction as to keep the pins 213 at one end of the cut-out portion; but if any one of the drawers 147 is opened, the abutting end of its associated cut-out portion urges shaft 151 to rotate and to wind up spring 152. After the first drawer 147 is opened, the opening of any additional drawer will simply cause its associated cut-out portion to follow after its respective pin, which had been moved away from the abutting surface when shaft 151 was rotated by the opening of the first opened drawer. In this way, every drawer 147 must be closed before shaft 151 is permitted to rotate to the position it had when no drawer was open. The same operation applies to the supply drawer and wrapping paper mechanism. The cam member 156 carried by the upper end of the shaft 151 is so arranged that, when the drawer is returned to its closed position and the arm 153 is rotated with the pin 213, the switch kick-off mechanism shown in Figures 15 and 16 and above described will be operated. In this arrangement, the electric motor will continue to run until all of the drawers have been closed. There may be also provided an indicating light 3' (Figs. 1 and 2) which will be lighted so long as the motor is kept running.

To one end of the shaft which supports the apertured drum 149 (Fig. 10) is secured a sprocket wheel 214 connected by a sprocket chain 215 with a sprocket wheel 104 on the shaft 103. Thus this drum is positioned in accordance with the selection of a compartment in receptacle 106 so as to permit only that drawer to open which corresponds to the selected compartment. Through a train of gears starting with 105, the gear 218 is operated, which rotates an indicating drum 217. On the periphery of this drum are marked the numbers of the various clerks, also whether the purchase is a charge or cash item. This drum is moved into its proper

position at the same time as the printing wheels, at the selection of the proper compartment in the ticket receptacle. It is apparent that as the drum 149 is rotated in accordance with the selection of the operator, the proper drawer will be permitted to open by reason of the rod corresponding to the drawer being permitted to move upwardly into one of the apertures in the drum. It will also be noted that, as the forward end of the arm 140 is moved downwardly by the cam 143 to engage the bifurcated member 139 of the drum, the opposite end of the arm 140 is lifted upwardly, thus carrying the frame 145 with it and moving it away from the pins 219, thus permitting the selected rod to move upwardly.

In Figures 25, 26, 27, and 28 there is illustrated a modified form of stitching mechanism adapted to be used with an identification plate which is to be retained in the customer's possession. The lower end of the stitcher head 220 is extended outwardly on both sides to form a guide 221 for a carriage 222 which conveys the identification plates 235, shown in Figures 29 and 30, to a point back of the stitcher head for printing on the ticket tape. The rear portion of the guide 221 is bridged across as at 223 to bear on the top of the identification plate during the printing operation for the purpose of resisting the upward movement of the platen. A tension spring 224 is attached at one end to the carriage 222 and at the other end to the bridge portion 223 for the purpose of positively returning the carriage and ticket to the proper printing position. The outer end of the carriage is formed into a handle 225. The side wall of the carriage is provided with a plurality of adjusting apertures 226, in which may be positioned a stud 227 forced inwardly under tension of a spring 228. This is to accommodate various sizes of tickets. The opposite end of the carriage is extended and reduced to form a cam portion 229 for raising and lowering an arm 230 which turns on a shaft 231 and brings a hook member 232 into and out of engagement with a controlling arm 223, urged by a spring 234 (Fig. 20) toward engaging position, but held against engagement by cam 229 that raises the arm 230. This arm controls the clutch mechanism, and, by the above provision, when the carriage is drawn outwardly to receive an identification plate, the arm drops away from the cam, causing the arm 232 to move upwardly and arrest the inward movement of the clutch control member 233. In this manner the machine cannot be accidentally operated unless the identification plate, carriage, and related parts are in their proper positions.

It is believed that the operation of the

mechanism will be apparent from the above description, but it may be briefly recapitulated as follows.

When the machine is to be operated, the operator first depresses the handle 130 on top of the arm 123 and moves the selecting arm around the quadrant until the operator's identification mark has been reached and as indicated by drum 217. As the handle is moved to the selected notch and quadrant, the ticket receptacle is also positioned through the shaft 103 and connected parts to bring the compartment belonging to the operator into alignment with the ticket discharge means, so that the ticket about to be printed will be discharged into the proper compartment. Simultaneously, through the connections described, the type wheel 188 is rotated, and the printing type corresponding to the clerk's number is brought into printing position. This also indicates whether the item to be registered is a charge or a cash item, since on the type wheel 188, the clerk's number can appear twice, each in combination respectively with a cash or charge character. This simply means that handle 130 must have two stops on quadrant 121 for each clerk: one stop corresponding to a charge transaction, and the other to a cash transaction. For example, the machine here illustrated is adapted for use by three operators. At the same time, the apertured drum 149 is rotated so that, at the proper time, the selected one of the rods 146 will be permitted to move upward, thus allowing the corresponding cash drawer to be opened. Also, at the same time that these operations take place, the indicating drum 217 is rotated, bringing into view of the purchaser the clerk's identification number, also whether the item is a charge or a cash item, this data corresponding to that on the printing wheel 138.

The price tag or pin ticket is then inserted in the ticket guide 68 on top of the ticket plate 45 coming below the extended portion of tape 69, and is pushed into position to receive the staple from the stitching mechanism.

As the arm 123 is depressed, the motor switch is closed and the motor begins operation. It does not, however, bring about any change in the position of the parts until the clutch operating member 233 (Fig. 4) is pressed inwardly, which in turn operates a lever 233¹ (see Figure 14) pivoted on a post 55 236 carried by the base 1 and having at its other end a spring pressed pawl 237 adapted to engage the ratchet wheel 12. As this is operated, it will move the upstanding member 10 out of the path of the pin 11 on the pawl 8, and allow the clutch mechanism to come 60 into operation, so that the shaft 6 will begin rotation, and the various activities of the machine will be set into motion through the train of gears 14 to 19 inclusive. The gear 65 14, through its cam 143, will press the arm

140 (Fig. 10) downwardly to engage the bifurcated member 139 upon the drum to hold it in a fixed position to receive the ticket. The gear 16 (Fig. 6), through its cam 23, then presses the cutting knife 26 downwardly into its open position, and the ticket tape is advanced by the friction wheel 26' (Fig. 5), which is driven by the shaft 21, only after the price tag has been severed and attached to the ticket tape. 70 75

The gear wheel 17, through its cam 43 and arm 42 (Fig. 3), rocks the lever 39 and operates the numbering wheels. At the proper time the cams 58, 59, and 60 on the shaft 62 (Figs. 20 to 24) of the gear wheel 19 will 80 operate the staple forming and stitching mechanism.

As soon as the ticket has been advanced beyond the end of the machine to a predetermined length, the cutting knife 26 (Fig. 6) 85 is permitted to swing upwardly to sever the ticket which has been gripped by the ticket discharge mechanism 74. As the knife moves upward, this mechanism operates just subsequently to the cutting of the ticket to discharge the same into the selected compartment of the receptacle in the manner already described. 90

At each operation of the machine, the ribbon is fed a step through the means controlled by the cam 96 on the shaft of the gear wheel 19. 95

The drawer corresponding to the selected compartment and the clerk's character (as indicated on drawer 217) is opened, as well 100 as the drawer containing wrapping material. A distinctive bell is also sounded by the mechanism shown in Fig. 11. Change can now be made to the customer and the package wrapped. As many price tickets can be inserted as desired, to operate the mechanism for completing the transaction for each customer and before the drawers are locked. Drum 165 (Fig. 8) indicates the number of articles sold in the transaction. The cash 110 and supply drawers are now ready to be closed, and as the drawers are moved inwardly toward the rear wall of the casing the shaft 151 is rotated through the action of one of the arms 153, which causes the cam 156 115 and the upper end of the shaft 151 to rotate, and, through the mechanism shown and described in Figures 15 and 16, breaks the circuit to the motor through the motor switch 136. At the same time the indicator drum 120 165, which has indicated the number of articles purchased since the preceding opening of the drawer, is returned to position by its spring 166. All other parts of the machine 125 also return to their initial position in readiness for another cycle of operation.

It may be here noted that the cam 156 has a dual function. It operates only after all drawers or supply compartments have been 130 closed due to provision of arms 153 and, if

any drawer or supply compartment remains open, the shaft 151 carrying the cam 156 cannot turn under the influence of the spring 152. This cam breaks the circuit and stops the 5 motor, as previously described, and also operates the pawl 158, and, through a pin 238 thereon, disengages the pawl 159 from the ratchet wheel 161, thus permitting the article indicator 165 to return to normal position under the influence of its spring 166.

There is shown in Figures 2 and 5 a dating mechanism which comprises conventional wheels for month, day, and year, and a finger wheel 243 mounted on a shaft 244 will turn 15 a gear carried by said shaft which meshes with the dating wheel for the day. A finger wheel 245 is carried by a sleeve 246 which also carries a gear wheel meshing with the dating wheel for the month. This construction in 20 and of itself is or may be old. It is noted that considerations of space require the dating mechanism to be positioned in advance of the printing and severing device, so that the date is really printed on the ticket in advance of 25 the one being severed by the machine.

Means may be provided for limiting the insertion of the pin ticket, and this may take the form of a stop carried by the stitcher head casting. This is desirable in order that the 30 pin ticket be severed in precisely the proper place.

It is also desired to emphasize the fact that the cutting knife is preferably made in some special shape, so that it will identify tickets 35 cut by the particular machine. A notch 61' (Fig. 21) can be provided in the blade 61 for this purpose. Thus if articles be not sold in regular fashion or if purloined, and if the holder of such an article should attempt to 40 secure a return of money for it, the impropriety of the sale can be readily detected by the absence of the secret punch or cut configuration.

The working parts of the machine will all 45 be enclosed in any suitable type of casing, and this has not been illustrated in the drawings. It in itself is no part of the invention, and any desired form of casing made of any suitable material may be employed, as found 50 necessary or desirable.

The mechanism takes much less time to operate than to describe it; and in fact an important advantage resides in the time saved by recording sales by this method. Furthermore the visible and audible signals provided insure against intended fraudulent tampering with the cash drawers. If the machine be operated without a price tag being first inserted the tape will nevertheless be 55 cut and supplemental data will be placed thereon and the whole placed in the corresponding receptacle 106. Thus improper operation of the machine can be detected by the absence of the required ticket stub.

60 It will be obvious that many features of the

invention are capable of being embodied in various forms, and that certain of them may be used in connection with other structures of varying types. The invention is to be regarded as limited, not by the illustrations, but only by the scope of the appended claims.

I claim as my invention:

1. In apparatus for obtaining records, mechanism for operating on tickets carrying data associated with merchandise, said mechanism providing a recipient to which the data are transferred, to obtain a record on the recipient truly corresponding to the data, and mechanism for supplying supplemental data to the recipient. 75

2. In apparatus for obtaining records, mechanism controllable by an operator for operating on tickets carrying data associated with merchandise, said mechanism providing a recipient to which the data are transferred, to obtain a record on the recipient truly corresponding to the data, mechanism for supplying supplemental data to the recipient, and means for rendering said combined record inaccessible to the operator. 80

3. In apparatus for obtaining records, mechanism for severing a ticket associated with merchandise, and carrying data, means providing a recipient to which the severed portion is transferred, to obtain a record truly 95 corresponding to the data, and mechanism for supplementing said data.

4. In apparatus for obtaining records from a plurality of tickets associated with articles of merchandise included in a transaction, means arranged successively to operate on each of said tickets in the transaction, to obtain a succession of records truly corresponding to the tickets, means for indicating the number of such operations, one or more 100 cash drawers, and means operable by closing the cash drawers for returning said indicating means to initial position upon the completion of the whole transaction.

5. In recording apparatus controllable by any of a plurality of operators, means forming a plurality of record-holding compartments, unavailable for opening by any operator, mechanism for operating on tickets incorporating premade, authorized data relating to merchandise, to obtain records truly corresponding to said data, a plurality of cash drawers, locking means for each of said drawers, and means under the control of each operator to select both a compartment and to deposit that operator's records therein, as well as to unlock a corresponding cash drawer. 115

6. In recording apparatus, means forming a plurality of closed record-holding compartments, mechanism for operating on tickets incorporating premade, authorized data relating to merchandise to obtain records truly corresponding to said data, a plurality of cash drawers, locking means for each of said 125 130

drawers, and means operating in response to the selection of a definite compartment for unlocking a corresponding cash drawer.

7. In an apparatus for recording the sale of merchandise, mechanism operating on tickets associated with the merchandise, to provide a recipient upon which data from the ticket is placed, means for interchangeably attaching to said mechanism an impression plate bearing data referring to the particular customer to whom the sale is made, and means whereby said plate serves to imprint a supplemental record on the recipient.

8. In recording apparatus controllable by an operator, mechanism for operating on a ticket incorporating premade, authorized data relating to merchandise, to obtain records truly corresponding to the data, means under the control of the operator for placing the record in any of a number of compartments, and means associated with said controllable means, for supplementing the record by adding thereto data identifying the operator.

9. In apparatus controllable by a sales person, a plurality of cash drawers, means providing a lock for each of the cash drawers, means providing a series of receptacles inaccessible to the person and corresponding respectively to the drawers, means providing a series of cards, means under the control of the person for selecting a receptacle and its corresponding drawer, and for recording identifying data on the cards, and means actuated to open only said selected drawer, whenever a card is deposited in the selected receptacle.

10. In apparatus controllable by a sales person, a plurality of cash drawers, means providing a lock for each of the cash drawers, means providing a series of receptacles inaccessible to the person and corresponding respectively to the drawers, a tape, means for cutting a portion of the tape, means under the control of the person for selecting a receptacle and its corresponding drawer, and for recording identifying data on the cut portion of the tape, and means actuated to open only said selected drawer, whenever said portion of tape is deposited in the receptacle.

11. In apparatus controllable by a sales person, a series of cash drawers, means providing a lock for each of said drawers, means providing a receptacle inaccessible to the person, a recording mechanism arranged to sever identifying tickets associated with merchandise, a tape, means to perform an attaching operation between the tape and the severed portion, as well as to cut the tape to form a ticket-carrying part, and to deposit said carrying part into the receptacle, and mechanism for selectively opening a cash drawer, substantially simultaneously with the depositing of the said carrying part.

12. In apparatus controllable by a sales

person, a series of cash drawers, means providing a receptacle inaccessible to the person, mechanism arranged to operate on tickets associated with merchandise to obtain a record for each ticket incorporating data truly corresponding to said tickets, a lock for each drawer, means whereby said record is placed in the receptacle, mechanism whereby a drawer is selected, and mechanism whereby said drawer is unlocked in response to the operation of the record-taking means.

13. In apparatus for obtaining records, mechanism for operating on a ticket associated with merchandise, to obtain a record truly corresponding to the ticket, and mechanism for supplying supplemental data to the record, said mechanism for supplying supplemental data including a holder for interchangeably carrying removable impression plates, said plates serving to impress a record relating to customers.

14. In apparatus for obtaining records relating to the sale of merchandise, a recording mechanism, means for removably accommodating a member for adding a supplemental record, said means being movable to a recording and to a non-recording position, said non-recording position being such that the member can then be accommodated by said means, and means whereby operation of the recording mechanism is prevented while the said means is in non-recording position.

15. In a recording apparatus controllable by an operator, means forming a plurality of record-holding compartments, unavailable for opening by the operator, mechanism for operating on tickets incorporating premade, authorized data relating to merchandise, to obtain records truly corresponding to said data, means for supplementing said data, a plurality of cash drawers, locking means for each of said drawers, and means under the control of the operator to select both a compartment and for depositing the record therein, as well as to unlock a corresponding cash drawer.

16. In a recording apparatus controllable by an operator, means forming a plurality of record-holding compartments, unavailable for opening by the operator, means for severing tickets associated with merchandise, the severed portions carrying data, said severing means including a cutter of such peculiar contour as to identify the severed tickets, means for supplementing the data, a plurality of cash drawers, locking means for each of said drawers, and means under the control of the operator to select both a compartment and for depositing the combined record therein, as well as to unlock a corresponding cash drawer.

In testimony whereof, I have hereunto subscribed my name.

MATTHEW KLEIN,
